DESIGN FOR A CIGARETTE HOLDER

Louis Reis, Cincinnati, Ohio

Application February 18, 1946, Serial No. 126,688

Term of patent 14 years

(Cl. D85—8)

To all whom it may concern:

Be it known that I, Louis Reis, a citizen of the United States of America, residing at Cincinnati, county of Hamilton, and State of Ohio, have invented a new, original, and ornamental Design for a Cigarette Holder, of which the following is a specification, reference being had to the accompanying drawing, forming a part thereof wherein:

I claim:

The ornamental design for a cigarette holder, as shown.

LOUIS REIS.
